Aposen Hand Vacuum, available in walmart.com, customer review oldest date Nov. 11, 2020 [online], [site visited Aug. 9, 2023], Available from the internet URL: <https://www.walmart.com/ip/Aposen-Hand-Vacuum-Cordless-Handheld-Vacuum-With-Charging-Dock-For-Pet-Hair/748512046> (Year: 2020).*

Primary Examiner — Jennifer Rivard*Assistant Examiner* — Jennylou M Binas(57) **CLAIM**

The ornamental design for a vacuum cleaner, as shown and described.

DESCRIPTION

FIG. 1 is a perspective view of a vacuum cleaner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the vacuum cleaner that form no part of the claimed design.

1 Claim, 8 Drawing Sheets(56)
